UNITED STATES PATENT OFFICE.

JAMES WILKINSON, OF LYNN, MASSACHUSETTS, ASSIGNOR TO GENERAL ELECTRIC COMPANY, A CORPORATION OF NEW YORK.

MARINE-TYPE-TURBINE SPEED GOVERNOR.

Application filed February 2, 1923. Serial No. 616,480.

To all whom it may concern:

Be it known that I, JAMES WILKINSON, a citizen of the United States, residing at Lynn, in the county of Essex, State of Massachusetts, have invented certain new and useful Improvements in Marine-Type-Turbine Speed Governors, of which the following is a specification.

The present invention relates to governing means such as are used in connection with elastic fluid turbine installations and the like, to control the supply of elastic fluid thereto, and has for its object to provide an improved governing means of the above-named type which is particularly adapted to turbines used in propelling ships.

According to my invention I provide a simple form of governing means for ship propelling elastic fluid turbines wherein I employ an auxiliary source of fluid pressure to operate the main throttle valve and a pilot valve which is actuated by changes in speed of the turbine to control said auxiliary source of fluid pressure.

I accomplish the object of my invention by employing a fluid pressure responsive means which will open and close the throttle valve in response to changes in the speed of the turbine with a certain predetermined time delay before completing the full operation of said valve.

My invention can best be understood by first considering the conditions which are met in the application of turbines to ship propulsion. The problem of controlling the speed of a marine turbine when under normal operating conditions is not a serious one as the turbine is normally under a load which remains constant as long as the propeller is submerged. There is, however, always a possibility of the load being thrown off the turbine by reason of a broken shaft, loss of the propeller or the propeller coming out of the water in a seaway or trough while cruising in rough weather.

It is this latter condition which my invention is primarily designed to meet. It will be seen that if the ship is traveling in a direction substantially transverse to the swells that the propeller will come out of the water in each seaway or trough. This is particularly true where the ship is lightly loaded and when the sea is extremely rough. As the propeller comes out of the water the turbine will speed up and unless a trip mecha-

nism is provided will either run away or be subjected to severe strains when the propeller again submerges because it will suddenly take up the load under full steam. This is objectionable for the reason that it creates violent strains on the turbine and associated parts.

Under the above condition the speed control mechanism now in general use will trip the throttle valve and shut down the turbine thus leaving the ship without propelling means at a time when it is imperative to have the ship under power. With the above type of control it has been found necessary to keep a man at the throttle valve, whose duty it is to open the same after each tripping when the propeller again submerges.

With my invention I intend to accomplish the latter operation automatically in response to the speed of the propeller.

In the present embodiment of my invention I show a turbine having a pressure oiling system. I propose to use the lubricating medium of such a system for operating the pressure responsive means which controls the throttle valve. This will not only insure a positive means for transmitting the forces from one correlated part to the other but in addition will provide against the turbine running without proper lubrication, as the throttle valve will close automatically upon failure of pressure in the oiling system.

Additional novel details of construction and combinations of apparatus will be hereinafter described, and the novel features which I believe to be characteristic of my invention will be definitely indicated in the claims appended hereto.

The features of construction and mode of operation will be understood by referring to the following description taken in connection with the accompanying drawings which show the preferred embodiments of my invention. Fig. 1 is a plan view of a turbine driving a propeller through speed reducing gears and shows the relative location of the different parts of my invention as applied thereto; Fig. 2 is a diagrammatic view of the different parts of my invention and shows their relation to each other; Fig. 3 is a partial sectional view of the speed responsive tappet governor and pilot valve which controls the fluid to and from the main valve piston; Fig. 4 is a sectional view of Fig. 3 taken along line A—A; Fig. 5 is a sectional

view of the pilot valve shown in Fig. 3, and taken along line B—B; Fig. 6 is a sectional view taken from Fig. 3 along line C—C; and Fig. 7 shows a modification of my invention wherein I employ a torsion device instead of the tappet arrangement shown in the other figures of the drawings. It also shows a sectional view of the pilot valve.

In the drawings a preferred embodiment 10 of my invention is shown wherein I utilize the oil pressure of the turbine pressure oiling system to operate the speed controlling valve. Referring to Figs. 1 and 2, my invention comprises a valve 10 of the balanced 15 pressure type mounted upon the steam chest 11 of the turbine 12 and in the main steam line 13. Attached to the valve 10 is a pressure cylinder 14 having a piston 15 mounted therein. The piston 15 is biased in a direction to close the valve by means of a spring 16 which spring represents any suitable means for rendering the valve self-closing. The valve is opened against the spring 20 action by admitting oil to the cylinder from the turbine oiling system through a pipe 17 which conducts the oil from a pilot valve 18. The pilot valve 18 thus controls the oil supply 25 to the cylinder 14 and is actuated by a tappet governor 19 which will be described in more detail hereinafter. In the drawing 30 I show the tappet governor 19 mounted on the reducing gear casing 20 adjacent the end of one of the shafts. It should be understood, however, that this tappet governor 35 can be mounted in any convenient location where means to operate the governor are available, as for instance at the end of the turbine shaft. Connected between the pilot valve 18 and the gear casing 20 I show the 40 pipe 21 which conducts the oil under pressure to the pilot valve 18 and from which the oil passes through the pipe 17 to the cylinder 14 or through the pipe 22 to an exhaust basin, depending upon the position 45 of the pilot valve 18. I also provide in addition to the above an over speed emergency tripping device 23 which is of the usual type comprising a plunger 24 or other centrifugal responsive device mounted upon a 50 rotating shaft 25 and adapted to strike a trigger 26 when a certain predetermined abnormal high speed is reached by the shaft 25, the latter being the main shaft of the turbine. The trigger 26 is movable when 55 struck by the plunger 24 to release a plunger rod 27. At 27^a is a spring which acts in a direction to force rod 27 downward when released from trigger 26. The plunger rod 27 is connected by a shaft 28 and a linkage 60 indicated at 29, with a shaft 30 of pilot valve 18 in such a manner that the downward movement of plunger rod 27 causes the shaft 30 to be rotated. When the shaft 30 is thus rotated it will close the pilot 65 valve 18 and render it inoperative and there-

by shut down the turbine. The connection between plunger rod 27 and shaft 28 is a lost motion connection of the usual type comprising a pin and slot which permits shaft 28 to be turned independently of rod 27 for actuating the valve 18 manually.

Referring now to Figs. 3 and 4, I show the pilot valve 18 having at one end the pipe 17 for conducting the oil under pressure to the cylinder 14 and against the piston 15 which operates the throttle valve 10. Entering and leading from the top of pilot valve 18 are pipes 21 and 22 which conduct the oil to and from the pilot valve 18 respectively. The pilot valve 18 is of the concentric sleeve type having a movable sleeve 31 which is capable of a reciprocating or a rotary movement. At one end of the sleeve 31 (see Fig. 5) four openings 32 are provided which align with four similar openings 33 in a stationary sleeve 34 surrounding the movable sleeve 31.

On the other end of the movable sleeve 31 is a web 35 which extends diametrically across said sleeve 31 and engages a slot 36 in the shaft 30 which is operated by the high speed emergency tripping mechanism. The slot 36 in shaft 30 is made sufficiently deep to allow full axial movement of the sleeve 31 in response to the tappet speed governor which is operatively connected with said sleeve as will hereinafter appear, but at the same time it prevents any rotary movement of the sleeve 31 except that which is caused by the rotation of shaft 30. The valve arrangement is such that rotation of the shaft 30, as by the tripping of the emergency governor or manually, causes the openings 32 to be carried out of alignment with openings 33 thereby cutting off the oil supply from pipe 21 to the interior of sleeve 31 and to pipe 17, which last supplies the throttle valve operating cylinder 14. Sliding the sleeve 31 to the right from the position shown also serves to cut off the oil supply from pipe 21 in a similar manner. With the above arrangement it will be seen that the pilot valve will operate in response to forces from two different sources; one the speed governor proper and the other the emergency trip mechanism.

When the turbine is running the sleeve 31 is normally held in the open position shown, with openings 32 and 33 in registration, by means of a bifurcated lever 37 which is journaled upon a stationary shaft 38 and mounted in a casing 38^a surrounding the tappet governor 19.

The lower end of lever 37 is offset and has two tongues 39 and 40 projecting at right angles therefrom in two different planes (see Fig. 6). The projecting tongues 39 and 40 respectively engage eccentric surfaces 41 and 42 of an eccentric governor weight 43. The eccentric governor weight 43 is pivot-

ally connected to an extension of a gearing shaft 44 by a pivot stud 45 which is offset from the center of shaft 44 and journaled in the light side of said governor weight. 5
Associated with the governor weight 43 is a spring 46 which under normal speed conditions tends to hold the governor weight 43 in such a position that the lower end of the lever 37 will be practically centered over the 10 end of shaft 44. The governor arrangement is such that at a predetermined speed above normal speed and below the speed at which the emergency governor is set to trip, the governor weight moves in a direction to 15 carry sleeve 31 to the right as viewed in Fig. 3 slidably a sufficient distance to cut off the oil supply from pipe 21.

Within the pilot valve 18 is a partition 47 which has an opening sufficiently large to 20 allow free movement of the shaft 30 and at the same time permit a predetermined amount of oil to flow therethrough, thus forming a restricted outlet for the oil. Connected to valve 10 is an operating lever 48 25 for use in opening the valve manually, and connected to shaft 30 of the pilot valve is a crank lever 49 for actuating the pilot valve manually.

Referring now to Fig. 7, I show a modification of my invention wherein I dispense with the tappet governor described above and substitute therefor a speed governor in the form of a torsion responsive device.

In the drawing 50 is a resilient shaft 35 coupling of a known type comprising interleaving tongues projecting from flanges on the respective shaft ends and resilient means interposed in the radial paths of said tongues. The two elements of this coupling 40 move circumferentially relatively to each other by amounts proportional to the load, and associated with such elements is a series of bell-cranks (not shown) which transmit an axial movement to a ring 51 45 shown in the drawing. The essential thing is that ring 51 moves axially in response to load changes. I preferably employ a coupling 50 and torsion responsive mechanism, as shown in my Patent No. 1,359,853, dated 50 November 23, 1920.

In this modification of my invention I use a pilot valve 54 which operates to open or close on axial movements only.

Cooperating with the ring 51 is a grooved 55 wheel 52 whose flanges engage the ring 51 and cause it to be moved in an axial direction in response to any axial displacement of the ring 51.

The grooved wheel 52 is mounted upon a 60 shaft 53 and is free to rotate thereon. The shaft 53 is mounted in a pilot valve casing 56 and is attached to a valve sleeve 55 which is open at both ends. Located on the valve sleeve 55 are a series of openings which 65 align with similar openings in the station-

ary lining sleeve 57 when the pilot valve is in the open position. Entering at the top of the pilot valve 56 is a pipe 58 which conducts the oil from the pressure source to the pilot valve 56 and leading from the bottom of the pilot valve 56 is a pipe 59 which carries the oil discharge to a suitable collecting basin or reservoir (not shown). Within the pilot valve casing 56 is a partition 61 having an opening sufficiently large to allow the shaft 53 freedom of movement and at the same time allow a predetermined flow of oil to pass therethrough from the interior of sleeve 55 to a discharge pipe 59. A pipe 60 is shown connecting the pilot valve 56 and the piston cylinder 14 of the main throttle valve 10.

The operation of my invention is as follows:—

To start a turbine equipped with my invention, the lever 48 mounted at the end of the throttle valve 10 is pulled to the left as shown in Fig. 2. This permits steam to enter the turbine and after being once started the turbine will be controlled automatically, as I shall point out below. I also provide a crank-lever 49, as shown in Fig. 1, projecting from the pilot valve 18 for shutting down the turbine when a deliberate stop is desired. This crank acts independently of the energy tripping mechanism because of the pin and slot connection between rod 27 and shaft 28, and when operated by hand rotates the valve sleeve 31 of the pilot valve 18 and shuts off the fluid pressure supply to cylinder 14, thereby causing the throttle valve 10 to close and thus stop the turbine.

Assume now that the turbine is running at normal speed and that the pressure of the oiling system is constant. Under these conditions, the various parts of my invention will be in the positions shown in the drawing. Valve 10 is held open in response to pressure exerted upon piston 15 by the lubricating oil passing through the pilot valve 18 when in the position shown in Fig. 3. At the same time a small quantity of oil will flow through the restricted opening 47 in the pilot valve to outlet pipe 22.

If now the speed of the turbine should become excessive by reason of the propeller coming out of the water, the weight 43 of the tappet governor 19 will overcome the effort made by spring 46 to hold it in its normal position and move to the left, upon its axis 45. This will cause the lower end of lever 37 to be moved to the left (see Fig. 3) by reason of its engagement with the member 43, and since lever 37 is pivoted midway its ends, the upper end of lever 37 will move to the right and close the pilot valve 18, thus shutting off the supply of fluid pressure to the cylinder 14. The spring 16 in the cylinder 14 will now cause the valve 10 to close and force the oil from

cylinder 14 through the restricted opening in member 47 of the pilot valve 18 from which it will flow to the oil reservoir through pipe 22.

- 5 As the valve 10 closes the steam supply to the turbine will be shut off and cause the turbine to slow down and as a result the weight 43 of the tappet governor will then return to its normal position in response to 10 the force exerted upon it by the spring 46. This will cause the pilot valve 18 to open again and permit the pressure of the lubricating fluid to be exerted upon the piston 15 and cause the valve 10 to open.
- 15 It will be seen from the above that such an arrangement will give a periodic opening and closing of the valve 10 in response to normal and abnormal speed conditions of the propeller respectively. These periodic 20 operations of the throttle valve 10 can be made to correspond to such periods of time as are found desirable.

Assume now that for some reason the above cycle of operation fails to occur and 25 that the turbine continues to speed up to a dangerous speed as, for instance, the speed at which the emergency tripping mechanism operates. This will cause the plunger 24 of the emergency tripping device 23 to 30 project from the shaft 25 because of centrifugal force. The plunger 24 will strike the trigger 26 which will release the plunger rod 27 and this will permit the shaft 28 to rotate in response to force exerted by 35 spring 27^a, and through suitable levers also cause the shaft 30 of the pilot valve to rotate through an arc of approximately 45° which is sufficient to close the pilot valve 18. This will shut off the supply of fluid pressure to the cylinder 14 and, as described 40 above, the throttle valve 10 will close and shut down the turbine. It will then be necessary to reset the emergency tripping device by hand before the turbine can again 45 be started, thus insuring a complete stopping of the turbine.

In the modification shown as Fig. 7 the 50 operation of my invention is substantially the same as described above with the exception that instead of a tappet governor operating the pilot valve sleeve 31, I provide means to operate a similar valve sleeve 55 in response to differences in torque exerted upon two cooperating coupling flanges, one on 55 the driving shaft and the other upon the driven shaft, which will transmit axial movement to the ring 51 and thus cause the valve sleeve to be moved within the valve casing 56 because of its engagement through the grooved wheel 52 with the ring 51.

When the pilot valve of modification 60 shown in Fig. 7 is in the position shown the oil under pressure will enter the pilot valve 56 through the pipe 58 and flow through the pipe 60 to the cylinder 14 in which it will

exert pressure upon the piston 15 and hold the valve 10 open. At the same time a small amount of oil will flow through the restricted opening in the partition 61 of the pilot valve, to the oil reservoir through the 70 pipe 59.

If now the propeller comes out of the water, the variation in torque upon the two cooperating flanges will cause the ring 51 to move axially and move with it the 75 grooved wheel 52. This will move the pilot valve sleeve 55 to the closed position and thus shut off the supply of fluid pressure to cylinder 14. The piston 15 will then be moved by the spring 16 to close the throttle valve 10, the oil within the cylinder being forced out of the cylinder 14 through pipe 60 and the restricted passage in partition 61 of the pilot valve to the outlet pipe 59.

Under normal conditions before the turbine comes to a complete stop the propeller will again submerge and the torque responsive coupling will cause the ring 51 to move to the left and open the pilot valve, thus allowing the oil pressure to be again exerted 90 upon piston 15. The piston will be moved by the pressure of the oil to open throttle valve 10, whereupon steam will again be admitted to the turbine.

In this modification I show no emergency 95 tripping means but it should be understood that such a means could be provided as shown in connection with the valve of Figs. 3 and 4 without departing from the scope of my invention.

It will be seen that in accordance with my invention in one embodiment thereof I provide a balanced self-closing throttle valve in the motive fluid supply line of a turbine and means actuated by the pressure 105 from the oiling system of the turbine, for holding said valve open.

In connection with such an arrangement I provide a pilot valve between the oil pressure supply and the means for holding the 110 throttle valve open, the pilot valve being movable to cut off the oil supply and permit the throttle valve to close.

To the pilot valve I connect a dual governing means comprising an overspeed 115 emergency-trip governor which closes the pilot valve when a certain maximum allowable overspeed is reached by the turbine, and a second governor which is operative to close the pilot valve only when the turbine 120 is operating under load and suddenly or momentarily loses said load in part or wholly, the second governor normally functioning before the speed reaches the predetermined maximum at which the emergency 125 governor is set to operate.

The second governor may be such that it is responsive to overspeed according to the arrangement shown in Figs. 3 and 4, thus being indirectly responsive to loss of 130

load or it may be directly responsive to loss of load according to the arrangement shown in Fig. 7, the result in either case being the same, that is, the throttle valve is permitted to close upon loss of load.

By utilizing the oil pressure from the turbine oiling system to maintain the throttle valve in the open position, a desirable safety feature is incorporated in the control means 10 for the turbine, in that the throttle valve will be permitted to close and thus stop the turbine in case the oil supply fails. Other means for operating the throttle valve may, however, be utilized in connection with the 15 dual governing means.

What I claim as new and desire to secure by Letters Patent of the United States, is:—

1. The combination with a prime mover having a valve mechanism, of means for 20 regulating said valve mechanism comprising a cylinder, a piston therein, a source of fluid pressure connected to said cylinder, a valve for controlling admission of fluid from said source to said cylinder, a speed 25 responsive means for operating said valve in one direction when the turbine exceeds its predetermined normal speed by a certain amount, and a second speed responsive device for operating said valve in another 30 direction when the turbine exceeds its predetermined normal speed by a still greater amount.

2. In combination with a prime mover having a valve mechanism, of a governor 35 mechanism therefor comprising a cylinder and a piston therein, a conduit for supplying fluid pressure to said cylinder, means connected in said conduit for controlling the supply of fluid pressure, said means comprising a normally open valve capable of 40 both axial and rotary movements, either of which movements serves to close the valve, a governor for moving the valve axially to control the turbine within certain limits and 45 a second governor which rotates the valve to control the turbine within other limits.

3. The combination with a prime mover having a throttle valve for controlling the admission of elastic fluid thereto, of an auxiliary source of fluid pressure for operating 50 said throttle valve, a conduit connected with said source through which the fluid pressure is supplied, means for controlling said auxiliary source of fluid pressure, comprising 55 a tappet governor, a valve operated thereby to open and close the auxiliary fluid pressure conduit in response to the speed of the turbine, and said governor being operative to close the valve when a certain normal 60 speed is exceeded and causing the valve to be open at all other speeds, and a second governor connected with the valve, said gov-

ernor being operative to close said valve only at speeds exceeding a predetermined maximum allowable speed.

4. In combination, a turbine adapted to ship propulsion, a throttle valve, a fluid pressure supply for operating said throttle valve, a second valve adapted to control said fluid pressure supply in such a manner that when said second valve is closed the throttle valve will be closed, and when opened the throttle valve will be opened, and means to operate said second valve comprising a tappet governor and a high speed tripping device each of which operate to close said second valve when the turbine exceeds predetermined speeds, the tappet governor operating at a speed lower than that at which the tripping device operates and causing the valve to automatically reopen when the speed at which said governor operates is exceeded from.

5. The combination with a prime mover having a motive fluid supply conduit connected therewith and a self-closing throttle valve in said conduit, of a fluid operated motor for moving said valve to the open position and for normally maintaining said valve in such position, a conduit through which operating fluid is supplied to the motor, a pilot valve in said conduit, the pilot valve being movable between the open and the closed positions to effect a corresponding operation of the throttle valve, independent 55 control means for moving the pilot valve between said last-named positions, a governor for the turbine connected with one of said control means, said governor being responsive to certain abnormal operating conditions of the turbine to effect a closing of the pilot valve, a second governor connected with the other of the control means, said governor being responsive to a certain predetermined speed whereat it operates to 100 close the pilot valve, and means forming a leakage opening in the operating fluid conduit between the pilot valve and the motor.

6. The combination of an elastic fluid turbine having a valve for controlling the admission of motive fluid thereto and a fluid-actuated motor for the valve, of a pilot valve for controlling the flow of fluid to said motor, said pilot valve being movable both axially and circumferentially, a governor for moving said pilot valve axially to control the turbine within certain limits, and a second governor which turns the pilot valve to control the turbine within other limits.

In witness whereof, I have hereunto set my hand this 30th day of January 1923.

JAMES WILKINSON.
